United States Patent Office

Des. 200,375
Patented Feb. 16, 1965

200,375

PORTABLE RADIOGRAPHIC EXPOSURE UNIT

Lawrence P. Feer, Cazenovia, N.Y., assignor to General
Motors Corporation, Detroit, Mich., a corporation of
Delaware

Filed Sept. 26, 1963, Ser. No. 76,745

Term of patent 14 years

(Cl. D83—1)

Fig. 1

Fig. 2

Fig. 3

Fig. 4

Fig. 5

FIG. 6

FIG. 7

FIGURE 1 is a front elevational view of a portable radiographic exposure unit, showing my new design;

FIGURE 2 is an elevational view of one side;

FIGURE 3 is a bottom plan view;

FIGURE 4 is a top plan view;

FIGURE 5 is an elevational view of the other side;

FIGURE 6 is a rear elevational view;

FIGURE 7 is a perspective view.

I claim:

The ornamental design for a portable radiographic exposure unit, substantially as shown.
